DESIGN FOR A BOTTLE OR SIMILAR CONTAINER

Edwin W. Fuerst, Toledo, Ohio, assignor to Owens-Illinois Glass Company, Toledo, Ohio,
a corporation of Ohio

Application October 19, 1934, Serial No. 53,693

Term of patent 14 years

To all whom it may concern:

Be it known that I, Edwin W. Fuerst, a citizen of the United States, and residing at Toledo, in the county of Lucas and State of Ohio, have invented a new, original, and ornamental design for a Bottle or Similar Container, of which the following is a specification, reference being had to the accompanying drawing, forming a part thereof.

In the drawing:

Fig. 1 is a perspective view of a bottle or similar container showing my design.

I claim:

The ornamental design for a bottle or similar container, substantially as shown.

Signed at Toledo, in the county of Lucas, and State of Ohio, this 16th day of October, 1934.

EDWIN W. FUERST.
